METHOD OF PRODUCING EXPANDED METAL LATH

Bernard T. Ballard and David M. Fleming,
Warren, Ohio, assignors to United States
Gypsum Company, Chicago, Ill., a corporation
of Illinois

Application November 30, 1939, Serial No. 306,860

8 Claims. (Cl. 164—6.6)

This invention relates to the method of making an improved expanded metal lath, and particularly flattened metal lath.

In making metal lath such as is commonly used as a plaster base, it has long been the practice to feed a thin narrow steel sheet or blank between cutters, which produce over-lapping rows of transverse slits to form bonds and strands. The slitting step has usually been carried out with rotary cutters, although other types of cutters have also been employed. This, in effect, is a shearing operation and results in adjacent strands being offset from each other perpendicularly to the plane of the sheet. Thereafter the slitted blank was expanded by progressively forcing the edges of the sheet in substantially opposite directions such as by means of an ordinary diverging chain or other type of diverging arm expander which is well known in the art. The resulting product was an expanded metal lath sheet of the type shown in Pearce Patent No. 1,743,800, having alternate rows of bonds lying at an acute angle to the plane of the sheet, and intermediate rows substantially at right angles to the plane of the sheet. Furthermore, the diamond-shaped openings of the prior art sheets lacked uniformity, not only in different sheets, but between different portions of the same sheet.

In carrying out the present method, the sheets are first slitted in accordance with the prior art practice. However, instead of expanding the slitted blanks with the strands offset from each other, the slitted blank is first passed between flattening means, such as pressure rolls, to force all the bonds and strands back into a flat or common plane.

This flattening step, which is not to be confused with any relatively slight flattening that may result from the use of ordinary feed rolls, very materially alters the subsequent expanding step and the resulting product, although the same type of expanding mechanism is employed with both the flattened and unflattened blanks. Due to the flattening of the slitted blank, the expanding thereof is far more uniform. Consequently the openings are likewise far more uniform than is the case when an unflattened sheet is expanded. A further effect of the flattening is that upon expansion all the bonds lie in substantially parallel planes at an acute angle to the plane of the expanded sheet.

The present invention also relates to the formation of flat expanded metal lath. It has been found that the prior art metal lath in which alternate rows of bonds were substantially at

right angles to the plane of the sheet could not be satisfactorily flattened. When sheets of this nature are passed through pressure rolls or other flattening means, many of the bonds perpendicular to the plane of the sheet are just mashed or crushed and are broken away from their adjoining strands. Even in the unfractured portions of the sheet, the shape and size of the openings vary considerably.

10 However, a sheet of expanded metal produced by the method hereinbefore described of slitting, flattening and expanding, and having the bonds all lying in substantially parallel planes at an acute angle to the plane of the sheet, may be passed between pressure rolls or other flattening means and satisfactorily flattened.

It is therefore an object of this invention to provide a method for producing expanded metal lath with openings of relatively great uniformity.

Another object is to provide a method for producing diamond mesh metal lath having all the bonds in substantially parallel planes at an acute angle to the plane of the sheet.

25 A further object of this invention is to provide a method for producing a sheet of flat expanded metal of substantially uniform strength and resistance to breaking throughout, and having openings of comparatively great uniformity.

30 Further objects and advantages will be apparent from the following description when considered with the accompanying drawing, in which—

Fig. 1 is a diagrammatic representation illustrating mechanism which may be used in carrying out the present method.

35 Fig. 2 is a plan view of a slitted blank having overlapping slits formed therein.

Fig. 3 is a cross sectional view taken along the line 3—3 of Fig. 2 and illustrates the offsetting of the strands and bonds in the slitted blank.

40 Fig. 4 is a cross sectional view through a transverse row of bonds showing the same after the blank has been slitted and then flattened.

Fig. 5 is similar to Fig. 4, but is a cross sectional view through a transverse row of strands.

45 Fig. 6 shows a sheet of prior art expanded metal in which alternate transverse rows of bonds are substantially perpendicular to the plane of the sheet and the intermediate transverse rows of bonds are at an acute angle to the plane of the sheet.

50 Fig. 7 shows a sheet of lath which may be used as a plaster base which has been formed by slitting, flattening and expanding, and in which all of the bonds are in substantially parallel planes at an acute angle to the plane of the sheet.

Fig. 8 is a view of flat metal lath formed from metal lath of the type illustrated in Fig. 7.

Referring more particularly to the drawing, there is shown a thin metal blank 1 which is passed between a pair of cutters such as rotary cutters 2. The slitting produces a blank 3 having transverse rows of bonds 4 and 5 and transverse rows of strands 6. The blank 3 is thereafter passed between pressure rolls 7, or other flattening means which force all the strands and bonds of the slitted sheet back into substantially a common plane, as shown in Figs. 4 and 5.

It has been found that the flattening step between the slitting and expanding tends to eliminate irregularity in the finished sheets as there is a uniform resistance to expansion.

The thus flattened and slitted blank is then fed to expanding mechanism such as a diverging chain expander diagrammatically illustrated at 8. This produces expanded metal lath such as shown in Fig. 7 in which all the bonds lie at an acute angle to the plane of the sheet in substantially parallel planes, and in which the openings are relatively uniform throughout. Expanded sheets of this character may then be fed through pressure rolls 9, or other flattening means, without fracturing of the sheet, resulting in a uniform, flat product, as illustrated in Fig. 8.

The method heretofore described in connection with the manufacture of diamond mesh metal lath is also applicable to the manufacture of other types, including herring-bone mesh, such for example as shown in Manofsky Patent No. 1,618,666, dated February 22, 1927.

In producing the herring-bone type of mesh, series of parallel slits are formed diagonally of the blank with alternate series being oppositely disposed. Reciprocating cutters are generally employed for this. When these blanks are expanded in the usual manner, such as by a diverging chain expander or by rolls and diverging guides, there is a tendency for some of the series of strands to twist. By flattening the blank before expanding to bring the offset strands back into a common plane, the resistance to expansion is substantially uniform and twisting of the strands is avoided. Therefore the expanded sheet is relatively uniform throughout.

It is to be understood that in carrying out the present method, various modifications and changes within the skill of the art may be made, and therefore we wish to be limited only by the scope of the prior art and the appended claims.

We claim:

1. The method of forming expanded metal lath of relatively great uniformity which comprises slitting a thin metal blank to form strands with adjacent strands offset from each other, flattening the slitted portions of said blank substantially without reducing the gauge thereof to bring the offset strand portions into a substantially common plane and provide a practically uniform resistance to expansion, and pulling the edges of said blank in substantially opposite directions while permitting said strands to arrange themselves at an angle to the plane of the expanded sheet during expansion thereof.

2. The method of forming expanded metal lath of relatively great uniformity which comprises slitting a thin metal blank to form strands with adjacent strands offset from each other, flattening the slitted portions of said blank substantially without reducing the gauge thereof to bring the offset strand portions into a substantially common plane and provide practically uniform

resistance to expansion, and continuously feeding said blank and simultaneously forcing the edges thereof in substantially opposite directions while permitting said strands to arrange themselves at an angle to the plane of the expanded sheet during expansion thereof.

3. The method of forming expanded metal lath of relatively great uniformity which comprises slitting a thin metal blank to form strands with adjacent strands offset from each other, flattening the slitted portions of said blank substantially without reducing the gauge thereof to bring the offset strand portions into a substantially common plane and provide a practically uniform resistance to expansion, and expanding the slitted and flattened portions of said blank by positively guiding the edges thereof in diverging directions while continuously advancing said blank, said strands being free to arrange themselves at an angle to the plane of said expanded sheet during expansion thereof.

4. The method of forming expanded metal lath of relatively great uniformity which comprises slitting a thin metal blank by forcing adjacent portions thereof in opposite directions substantially perpendicular to the plane of the blank to form strands offset from each other, rolling the slitted portions of said blank substantially without reducing the gauge thereof to bring the offset strand portions into a substantially common plane and provide a practically uniform resistance to expansion, and thereafter expanding the slitted and flattened portions of said blank by positively guiding the edges thereof in diverging directions while continuously advancing said blank, said strands being free to arrange themselves at an angle to the plane of said expanded sheet during expansion thereof.

5. The method of forming herringbone metal lath which comprises slitting a thin metal blank to form alternate series of oppositely disposed offset strands, flattening the slitted portions of said blank substantially without reducing the gauge thereof to bring said offset strand portions into a substantially common plane and provide a practically uniform resistance to expansion, and thereafter expanding the slitted and flattened portions of said blank by positively guiding the edges thereof in diverging directions while continuously advancing said blank, said strands being free to arrange themselves at an angle to the plane of said expanded sheet during expansion thereof.

6. The method of forming diamond mesh expanded metal lath which comprises slitting a thin metal blank to form strands and bonds with adjacent strands offset from each other, flattening the slitted portions of said blank substantially without reducing the gauge thereof to bring all said bonds and strands into a substantially common plane and provide a practically uniform resistance to expansion, and thereafter positively guiding the edges of said blank in diverging directions while continuously advancing the same to form an expanded sheet, said bonds being free to arrange themselves in substantially parallel planes at an angle to the plane of said expanded sheet during the expansion thereof.

7. The method of forming flat expanded metal lath which comprises slitting a thin metal blank to form strands with adjacent strands offset from each other, flattening the slitted portions of said blank substantially without reducing the gauge thereof to bring the offset strand portions into a substantially common plane and provide

a practically uniform resistance to expansion, pulling the edges of said blank in substantially opposite directions and causing said strands to arrange themselves at an angle to the plane of the expanded sheet during expansion thereof, and flattening said expanded sheet to force all parts thereof into substantially a common plane.

8. The method of forming flat diamond mesh expanded metal lath which comprises slitting a thin blank to form strands and bonds with adjacent strands offset from each other, flattening the slitted portions of said blank substantially without reducing the gauge thereof to bring all

5 said bonds and strands into a substantially common plane and provide a practically uniform resistance to expansion, positively guiding the edges of said blank in diverging directions while continuously advancing the same to expand said blank and cause said bonds to arrange themselves at an acute angle to the plane of the expanded sheet, and rolling said sheet to bring all parts thereof into a substantially common plane.
